DEVICE COMPRISING ONE OR MORE PUSH BUTTONS

Friedrich Lampe and Friedrich Laa, Vienna, Austria, assignors, by mesne assignments, to North American Philips Company, Inc., New York, N. Y., a corporation of Delaware

Application July 20, 1955, Serial No. 523,247

Claims priority, application Austria September 10, 1954

5 Claims. (Cl. 200—18)

This invention relates to a push-button arrangement of the type used in radio apparatus. In a known structure comprising one or more push buttons and a locking member preferably for each individual push button has been suggested, each push button being supported by a switching element comprising the locking member, which switching element is slidable in the pushing direction for controlling a switching mechanism and is tiltable about an axis, preferably imaginary, at right angles to the direction of sliding for locking or releasing the locking member.

Consequently, it is possible by means of each button to choose between two positions of the switching mechanism.

The invention underlies the recognition that during the tilting movement at least part of the switching element may exhibit a component of movement oppositely directed to the corresponding direction of sliding, that is to say after a button has been pushed, an opposite movement of part of the switching element may follow during tilting, and when a button is released, a movement opposite to the subsequent sliding movement may occur during tilting. Consequently, during pushing and locking and also during the release and the subsequent sliding movement the movement of part of the switching element may each time be reversed.

For demagnetising recording heads and reproducing heads in magnetic recorders numerous circuits are known for preventing or obviating residual magnetism. In a known simple method the head is connected to a charged capacitor of corresponding capacity to form an oscillatory circuit. The decreasing oscillations with which the capacitor then discharges cause the head to be demagnetised completely. The circuit thus consists in that the connection between the head and the amplifier is interrupted, a connection between the head and the capacitor is established and then interrupted again, and at last the head is again connected to the amplifier. This sequence of switching operations may, of course, be brought about in a very simple manner by arbitrary operation of the switch. However, it is common practice that this sequence of switching is effected automatically by operation of the members for recording and reproduction.

According to the invention, at least part of the switching element during tilting exhibits a component of movement oppositely directed to the corresponding direction of sliding, said component of movement being used to control the switching mechanism, so that the change in position thereof is limited to part of the operating time of the device.

Consequently, the device according to the invention permits not only of bringing about a permanent change in position of a switching mechanism but also of obtaining a change in position for a determined period. The speed of the movement of the button only acts upon the duration of the change in position. Irrespective of this speed, however, it is always ensured that the change in position actually takes place and is obviated at the end of the operating period.

2

In one advantageous embodiment of the device according to the invention, each part of the switching element on account of the particular shape of the locking surface of the locking member exhibits a component of movement oppositely directed to the corresponding direction of sliding, so that each arbitrary part of the switching element may be utilised to control the switching mechanism.

In order that the invention may be readily carried into effect, it will now be described, by way of example, with reference to the accompanying drawing showing an example of switching in a magnetic recorder for recording and reproduction.

Figs. 1 and 2 show one embodiment comprising two buttons intended for recording and reproduction, respectively.

Fig. 1 is a sectional view taken along the line I—I of Fig. 2, but in which, contrary to Fig. 2, the two buttons are assumed to occupy positions.

Fig. 3 shows the button of Fig. 1 at the moment of being locked and

Fig. 4 shows this button in the completely locked position.

A carrier plate 1 has secured to it a U-shaped clasp 23 by means of rivets 24 and 25. The two free limbs of the 25 U are bent inwardly, thus forming extensions 26 and 27. An aperture 28 of the carrier plate 1 is such that the switching elements 29 and 30 are not guided by it. This is effected in apertures 31, provided in the extensions 26 and 27, and in apertures 32 of the clasp 23. Springs 33, 34 are secured, on the one hand, to extensions 35 and 36 of the switching elements 29 and 30 and, on the other, to extensions 37, 38 of the clasp 23. By means of a pin 39, it is possible to operate a lever 40 connected by way of a rod 41 to a switching mechanism for recording or 35 reproduction. The upward movement of the elements 29 and 30 is limited by the parts moved by them. The downward movement of the elements 29 and 30, if the elements have not been locked beforehand, is at any rate limited due to the extensions 35, 36 abutting against the 40 parts 26, 27. The elements 29, 30 are operated by buttons 42, 43. The upper surfaces 44 thereof are of a particular shape to facilitate the operation.

A locking member 45 is of a shape such that at least an edge obtained by intersection of surfaces 46 and 47 45 and engaging in the locked position with the lower side of the U-clasp 23 remains in contact with the lower side of the clasp 23 during tilting of the element 29. This takes place, for example, as shown in Fig. 5, in which the surface 46 is a flat surface making an angle α with the surface 47 which is the complement of an angle β , that is the angle through which the surface 47 has been tilted. The locking member of lever 30 is of a similar shape. Owing to this particular shape of the surface 46 it is ensured that each part of the switching elements exhibits a 55 component of movement which is opposite to the corresponding direction of sliding as long as the edge of the surface 46 slides along the lower side of clasp 23. The terminus of the element, is indicated by 48 in the case of the element 29, thus in Fig. 3 is farther away from 60 the lower side of clasp 23 than in Fig. 4. The displacement in the direction of sliding of the element is during tilting oppositely directed to the preceding or subsequent sliding movement.

The reversal in the direction of movement of the elements 29 and 39 during tilting is utilised to control the demagnetising device indicated diagrammatically by springs 49, 50, 51.

The U-clasp 23 comprises, at each end, a prolongation 52 projecting from the extensions 26, 27, respectively. 70 Between the prolongations 52, a lever 54 is pivotally arranged on a shaft 53. The lever 54 is maintained in a rest position by a spring 55 and an abutment 56 provided

on a lateral part 52, which rest position is chosen to be such that the points 48 just engage the lever 54 in the locked positions of the elements 29 and 30. The lever 54 occupies the same position when the buttons are released. The lever 54 has a suitably positioned thickened part 57 which causes the spring 50, which is in contact with the spring 49 at the rest position of the lever 54, to be switched over to the spring 51 as soon as the lever 54 is pushed and brought out of its rest position. This is effected automatically each time either of the two push buttons is locked and released.

When the spring 50 is connected to the magnetic head, the spring 49 is connected to the amplifier and the spring 51 is connected to the demagnetisation capacitor, it is found that each switching operation of the buttons 42, 43 involves demagnetisation of the head.

Since the distance between the point 48 and the shaft 53 is very small, but the distance between the thickened part 57 and the shaft 53 is comparatively large, a small shift of point 48 amounting to some tenths of millimetres is sufficient to provide a sufficient stroke of the thickened part 57.

It will readily be evident that, during the tilting of the elements 29, 30, the parts located under the apertures 31 and 32, respectively, perform movements, components of which are oppositely directed to the corresponding sliding movement. However, this tilting movement is superposed on the shaft, the magnitude and the direction of the displacement resulting from the tilting movement being determined by the shape of the surface 46. If the part of the element projecting above the apertures 31, 32 is very long, the shift resulting from tilting is immaterial. Consequently, it is advantageous for the surface 46 to have a shape such that the shifts of all parts of the element resulting from tilting is sufficient to control the switching mechanism.

The present invention is not limited to the use in connection with a demagnetising device. It is also independent of the manner in which the sliding movement of the switching element is transmitted, neither is it essential for the edge which during tilting slides along the lower edge of clasp 23 to be located in the surface 47 and hence at the end of the surface 46, though the maximum stroke is thus obtained. It is not necessary for the movement of a point to be derived from the lower extremity of the switching element, it being possible to choose therefor any arbitrary other point.

What is claimed is:

1. A push-button device comprising a carrier plate, a frame member secured to said carrier plate, at least one

switching element having a locking portion and slidable in said frame member, a switch mechanism associated with said push-button device and controlled by the movement of said switching element, the latter being slidable in a direction substantially transverse to said switch mechanism to actuate the same and tiltable about an axis substantially perpendicular to the direction of sliding to further actuate said switch mechanism while said switching element is locked against further sliding movement by said locking portion.

2. A push-button device as set forth in claim 1 further comprising an elongated lever engaging at one end said switch mechanism, means pivotally mounting said lever on said frame for transmitting the movement of said switching element.

3. A push-button device as set forth in claim 2 wherein said lever is so constructed that the same switch mechanism is controlled by different switching elements.

4. A push-button device comprising a carrier plate, a frame member secured to said carrier plate, at least one switching element having a locking portion and slidable in said frame member, said locking portion being a re-entrant part having opposite sides angularly positioned relative to each other, the distance between said opposite sides at the opening of said re-entrant part being smaller than the distance between said opposite sides in the rear of said re-entrant part, a switch mechanism associated with said push-button device and controlled by the movement of said switching element, the latter being slidable in a direction substantially transverse to said switch mechanism to actuate the same and tiltable about an axis substantially perpendicular to the direction of sliding to further actuate said switch mechanism while said switching element is locked against further sliding movement by said locking portion.

5. A push-button device as set forth in claim 4 wherein said locking portion has a shape such that at least one edge thereof remains in engagement with said frame member during the tilting of the switching element.
